HAND TOOL FOR CUTTING OR PUNCHING OR THE LIKE

Hans K. Lorentzen, Brick Township, Ocean County, N.J.,
assignor to Levolor Lorentzen, Inc., Hoboken, N.J., a
corporation of New Jersey

Filed May 12, 1966, Ser. No. 2,279

Term of patent 14 years

(Cl. D54—13)

FIG.4

FIG.5

FIG.6

FIGURE 1 is a side elevation, from the left-hand side of my hand tool for cutting or punching or the like.

FIGURE 2 is a side elevation, from the right-hand side of my hand tool for cutting or punching or the like.

FIGURE 3 is a top plan view, looking from the top of FIGURE 1.

FIGURE 4 is a plan view, corresponding to FIGURE 3, but with the tool turned edge for edge about the longitudinal axis of the tool.

FIGURE 5 is an end elevation, looking from the left-hand end of FIGURE 1.

FIGURE 6 is an end elevation, looking from the right-hand end of FIGURE 1.

The dot-dash lines showing the dies and accessories in the several views are disclosed for illustrative purposes only.

I claim:

The ornamental design for a hand tool for cutting or

punching or the like, substantially as shown and described.
